United States Patent Office

Des. 190,868
Patented July 11, 1961

190,868

DICTATING MACHINE

Ernest F. Thomson, Forest Hills, N.Y., and Robert G. Smith, Norwalk, Conn., assignors to The Soundscriber Corporation, North Haven, Conn.

Filed Dec. 27, 1960, Ser. No. 63,353

Term of patent 14 years

(Cl. D26—14)

FIG. 1 is a front perspective view of a dictating machine, showing our new design;

FIG. 2 is a front elevational view thereof;

FIG. 3 is a right side elevational view thereof;

FIG. 4 is a left side elevational view thereof; and

FIG. 5 is a rear elevational view thereof.

We claim:

The ornamental design for a dictating machine, as shown.
